[57] **CLAIM**

The ornamental design for a hockey puck with polygon perimeter, as shown and described.

DESCRIPTION

FIG. 1 is a perspective view of a hockey puck with polygon perimeter showing my new design;

FIG. 2 is a top view; bottom view being a mirror image thereof; and,

FIG. 3 is a side view thereof, the opposite side view being a mirror image.

The broken line disclosure in FIGS. 1 and 2 is for illustrative purposes only and forms no part of the claimed design.
